UNITED STATES PATENT OFFICE

ROBERT H. M. ERDMANN, OF JAMAICA, NEW YORK

SUPERHEATER FOR BOILERS

Application filed December 20, 1928. Serial No. 327,275.

The present invention relates to improvements in attachments for domestic heating boilers, and has reference more particularly to a superheater for association with the boiler whereby the steam liberated from the boiler is superheated before entering the pipes or mains that lead to radiators and other like heating apparatus.

One of the important objects of the present invention is to provide a superheater attachment for boilers wherein the hot gases escaping from the fire box of the boiler may be utilized to advantage in superheating the steam prior to the discharge of the gases into the chimney.

Another important object is to provide a superheater than can be readily and easily installed without necessitating any material alterations of the parts of the boiler or the smoke flue with which the superheater structure is associated.

Another object is to provide a superheater of the above mentioned character that is simple in construction, inexpensive, strong and durable and further well adapted to the purpose for which it is designed.

Other objects and advantages of the invention will become apparent from the following description when taken in connection with the accompanying drawings.

In the accompanying drawings wherein like reference characters indicate corresponding parts throughout the several views:

Figure 1 is a side elevation of the superheater embodying my invention showing the manner in which the same is associated with a domestic boiler and the smoke flue extending therefrom.

Figure 2 is a vertical sectional view taken approximately on the line 2-2 of Figure 1.

Figure 3 is a horizontal section taken substantially upon the line 3-3 of Figure 1 looking in the direction of the arrows.

Figure 4 is a detail perspective view of the manifold forming a salient part of the present invention, and

Figure 5 is a detail perspective view of one of the U-shaped pipe sections that is operatively connected with the manifold.

In the drawings wherein for the purpose

of illustration is shown the preferred embodiment of my invention, the numeral 1 designates generally a conventional domestic boiler that in the present instance is provided with two steam outlets denoted by the reference characters 2 and 3, respectively, and a sectional pipe 4 has communication with the upwardly extending outlets at the top of the boiler in the manner as clearly illustrated in Figure 1. The smoke flue that leads from the fire box of the boiler to the chimney 5 is shown at 6 also in Figure 1, and in order to operatively associate my superheater with the smoke flue, the intermediate section of the smoke flue is removed and my superheater is positioned between the end sections of the smoke flue.

My improved superheater includes a rectangular casing 7 that is open at its respective ends, suitable closures 8 and 9 being removably fitted on the respective ends of the rectangular casing and each of these closures is formed with a flanged central opening 10 for communication with the respective end sections of the smoke flue 6.

The superheater further includes the provision of a rectangular shaped manifold 11 that is constructed from a hollow casting. The pipe 4 extends through the front side of the casing 7 and is secured at its free end within an opening formed in the front end of the manifold, which opening is denoted by the reference character 12. Similar openings 13 are formed in the opposite sides of the manifold adjacent the rear end portion thereof, and steam outlet pipes 14 are fitted at one end in the respective openings 13, these outlet pipes extending through the opposite sides of the casing 7 and leading to radiators or other heating apparatus (not shown). The pipes 4 and 14 cooperate to support the manifold 11 centrally within the upper portion of the casing 7.

While I have shown and described the casing and the manifold as being rectangular in shape, it is to be understood that the same may be cylindrical if so desired, and I do not wish to limit myself to the particular contour of either the casing or the manifold.

The bottom of the manifold is formed with

pairs of openings 15 and each of the openings formed in the manifold is reinforced. Vertically disposed pipes 16 are secured at their upper ends in the several openings 15 and as is clearly indicated in Figures 2 and 5, a nut 17 is threaded on each pipe for disposition against the outer face of the respective sides or bottom of the manifold 11.

A substantially U-tube 18 is operatively connected with the lower ends of each pair of depending pipes 16 and suitable couplings 19 afford a means for connecting the upper free ends of the arms of each U-tube to the lower ends of the respective pair of vertical pipes 16 and the U-tubes are arranged in spaced relation with respect to each other as clearly indicated in Figure 1. The lower ends of these U-tubes terminate a slight distance above the bottom of the casing.

The use of my improved super-heater is 20 thought to be readily obvious from the construction disclosed and it will be apparent that when the hot gases and products of combustion are discharged from the fire box of the boiler into the flue 6, the same will pass 25 upwardly into the casing 7 around the spaced U-tubes and the pipe 16 as well as the manifold 11, thus thoroughly heating the steam that circulates through the manifold and which may be in the several U-tubes and the 30 pipes connecting the same with the manifold before the steam is caused to be delivered to the heating apparatus such as the radiators located in different parts of the house or building. Globules of water which may be 35 in the steam when it enters the manifold 11 will collect in the lower ends of the U-tubes which are disposed immediately above the intake opening of the casing and be vaporized into steam by the intense heat at this point 40 of said casing. The waste of products of combustion will pass through the top of the casing into the upper section of the smoke flue and will be discharged into the chimney 5.

It will thus be seen from the foregoing description that I have provided a superheater 45 attachment for domestic boilers that will at all times be positive and efficient in carrying out the purposes for which it is designed, and due to its simplicity, the superheater can be 50 installed in the heating system without necessitating any material alterations.

Furthermore, the parts constituting the 55 superheater are so constructed as to permit the same to be readily and easily assembled or disassembled, and access to the various parts arranged within the casing may be obtained whenever necessary.

While I have shown the preferred embodiment of my invention it is to be understood 60 that minor changes in the size, shape, and arrangement of parts may be resorted to without departing from the spirit of the invention and the scope of the appended claim.

Having thus described the invention, what

I claim as new and desire to secure by Letters Patent is:—

In a super heater for association with a smoke flue that leads from a boiler, a vertically disposed casing mounted exteriorly 70 of the boiler forming a section of the smoke flue and having intake and outlet openings at its lower and upper ends, respectively, a manifold arranged within the casing and spaced from the inner walls thereof, a steam supply pipe extending from the boiler through one 75 wall of the casing into the manifold, superheated steam outlet pipes extending from the manifold through opposite walls of the casing, said pipes constituting means for supporting the manifold in the casing in spaced relation to the walls thereof, and a series of spaced U-tubes communicating at their upper 80 ends with the bottom of the manifold and having their lower ends disposed adjacent the intake opening in the casing and adapted to collect water globules from the steam in the manifold and vaporize said globules, the steam in the manifold being superheated by the products of combustion passing upward- 85 ly through the casing from the smoke flue.

In testimony whereof I affix my signature.

ROBERT H. M. ERDMANN.
